United States Patent Office

Des. 188,396
Patented July 12, 1960

188,396

HOUSEHOLD PAN OR SIMILAR ARTICLE

Charles O. Bliss, 6674 Santa Monica Blvd.,
Los Angeles, Calif.

Filed Apr. 14, 1958, Ser. No. 50,456

Term of patent 14 years

(Cl. D58—12)

FIG. 1

FIG. 2

FIG. 3

FIG. 4

Fig. 1 is a perspective view of a household pan or similar article showing my new design;

Fig. 2 is a side elevation thereof;

Fig. 3 is an end elevation thereof;

Fig. 4 is a cross-sectional view thereof taken on the line 4—4 of Fig. 2 on an enlarged scale.

The design for the pan disclosed is characterized by the centrally disposed indentation on each side and end of the pan as shown.

I claim:

The ornamental design for a household pan or similar article, substantially as shown and described.
